UNITED STATES PATENT OFFICE.

ALFRED LAAKSO, OF WAKEFIELD, MICHIGAN.

VENTILATOR.

1,289,821.

Specification of Letters Patent.

Patented Dec. 31, 1918.

Application filed August 31, 1917. Serial No. 189,147.

To all whom it may concern:

Be it known that I, ALFRED LAAKSO, a citizen of the United States, residing at Wakefield, in the county of Gogebic and State of Michigan, have invented new and useful Improvements in Ventilators, of which the following is a specification.

This invention relates to improvements in ventilators for buildings.

In carrying out my invention, it is my purpose to construct a ventilator having its parts so arranged that currents of air will be directed through suitable openings in the cowl or foot thereof, through certain flues in the body or stack of the device, which currents not only supply fresh air to the interior of the buildings, but tend to direct the foul air of the building through certain of the flues in the body or stack which find an outlet passage in the hood or cowl.

It is a further object of the invention to provide a ventilator of this class wherein the down currents of fresh air will be regulated and wherein the up currents of foul air will find a ready outlet passage.

It is a further object of the invention to produce a device of this character wherein the air passages in the cowl are fully protected so that rain, snow or sleet cannot enter therethrough, but wherein the free passage of air currents in both a downward and upward direction will not be interfered with.

It is a still further object of the invention to produce a ventilator for buildings comprising a tubular member or stack having a plurality of flues therein, to arrange upon the said stack a cowl having vertically disposed passages protected by suitable plates to shield the same from the elements but which shields, however, do not interfere with the free passage of air through the said cowl, and to further arrange a valve between the cowl and stack whereby the passage of fresh air into the building and the outlet of the stale air from the building may be regulated to suit atmospheric conditions.

It is a still further object of the invention to produce a device of this character which may be readily installed upon any building, which shall be of a comparatively

simple construction, but which is thoroughly efficient for the purpose designed.

With the foregoing objects in view, and others which will appear as the nature of the invention is more fully understood, the improvement resides in the construction and operative arrangement of parts set forth in the following description and falling within the scope of what is claimed.

In the drawings,

Figure 1 is a side elevation of the improvement as applied on the roof of a building.

Fig. 2 is a sectional view approximately on the line 2—2 of Fig. 1.

Fig. 3 is a vertical sectional view approximately on the line 3—3 of Fig. 1.

Fig. 4 is a sectional view approximately on the line 4—4 of Fig. 1.

Fig. 5 is a bottom plan view of the cowl.

Fig. 6 is a perspective view of the valve.

Fig. 7 is a bottom plan view of the tubular body or stack.

The roof 10 of a building 11 is provided with a suitable round opening receiving the lower or inner end of the tubular body of stack 12 of my improvement. The stack has secured thereon a suitable flanged collar 13 which surrounds the opening in the roof and which is secured to the roof. The tubular stack 12 is provided with right angularly arranged partitions 14 extending the entire length of the said stack dividing the interior thereof into four separate flues 15—15. The stack 12, adjacent to its outer end, and upon its outer surface, is provided with a plurality of spaced spring fingers 16.

The hood or cowl for the tubular stack 12 is broadly indicated by the numeral 17, the same also comprising a tubular body having a conical top 18. In the top, and at a suitable distance inward of the edge thereof is secured, in any desired or preferred manner, an annular member or ring 19, while at the bottom of the said cowl is arranged a similar ring 20. The rings 19 and 20 are connected by a series of inner and outer members 21 and 22 respectively, the said members in connection with the rings forming the side or body of the cowl.

The inner members, it will be noted, by reference to the drawings are approximately

semi-cylindrical in cross section having their edges flanged inwardly, as at 23, and these flanges are secured, in any desired or preferred manner, to the inner periphery of the 5 ring members 19 and 20, the lower edges of the said semi-cylindrical members being projected a suitable distance below the lower ring member 20, as clearly illustrated by the drawings. The outer members 22 comprise 10 plates which are centrally bent upon themselves, so that the same comprise angle members and the edges of these members are secured to the outer periphery of the ring members 19 and 20, in such a manner as to 15 each bridge two of the inner members 21. The outer members or plates are properly spaced away from each other as are the inner members 21, and the spaces provided between the said spaced inner and outer 20 members provide both the air entrance and the air outlet passages of the device. The cowl is designed to be slipped over the outer end of the stack 12, certain of the cross sectionally U-shaped members comprising the 25 inner wall of the cowl, being engaged by the spring fingers 16 to effectively sustain the cowl upon the stack. The arrangement of the inner and outer walls of the cowl, providing the air passages therebetween is such 30 that the air will take a tortuous path or direction in entering the stack and be directed through the flues thereof to the building, and likewise, the air from the building will take a similar path in finding an exit 35 through the passages in the cowl. The arrangement is also such that regardless of the operation of the air currents on the exterior of the building, certain of such currents will be directed through certain of the 40 passages in the cowl, and be likewise directed through certain of the flues in the stack, such air currents creating a circulation of air in the building and having a tendency to force the foul air through certain other flues 45 in the stack and through certain other passages in the cowl.

To regulate the inflow and outlet of air currents, I provide a valve broadly indicated by the numeral 24, the same including a flat 50 cylindrical top plate 25, having upon its outer face a circular band or ring 26. While secured to the inner face of the said top 25 is two right angularly disposed plates 27—27, each, in the nature of a right angular member, and the apex of these plates are spaced away from each other, whereby both of the 55 said plates may be snugly received in two of the diametrically opposite flues 15 in the stack 12, the said plates serving as protecting means for the valve proper.

To the plate or top 25 of the valve 24, near the center thereof, is secured one end of a flexible element preferably in the nature of a chain 28, the said chain being trained around

a grooved pulley 29 journaled in a suitable 65 hanger 30 that is secured in the center of the conical top 18 of the cowl 17. The top 25 of the valve 24 is also provided with an opening 31 through which the said chain passes, and whereby the said chain may be 70 directed through one of the flues 15 of the stack 12, the said flues having a guide loop 32 for the said chain. The end of the chain is provided with a ring member 33, the chain being of a length so that the said ring may 75 be arranged in convenient proximity to the operator of the valve from the interior of the building, and upon the said interior of the building is arranged suitable means for holding the chain, whereby the valve may 80 be retained in proper regulated position. When the valve is in its closed position, the top 25 thereof, will contact with the outer end of the stack, and by raising the said valve the determined volume of air may be 85 let into the building and likewise, a determined volume of air may be let out of the building, and from the foregoing description, when taken in connection with the drawings, the simplicity and advantages of 90 the construction will be apparent without further detailed description.

Having thus described my invention, what I claim is:

1. In a ventilator for buildings or the like, 95 a stack, spring fingers thereon, a cowl including a conical top, spaced rings, an inner and an outer series of channeled members having their edges secured to the inner and outer surfaces of said rings and connecting means between the top and the outer series of members, and certain of the inner series of said members designed to engage with the spring fingers, whereby to hold the 100 cowl upon the stack.

2. In a ventilator for buildings or the like, a stack having its outer surface provided with a series of concentrically arranged spaced fingers, a cowl including a top and a body constructed of spaced rings and an 110 inner and outer series of channeled members having their edges secured to the inner and outer surfaces of the rings, certain of said inner members designed to be engaged by the spring fingers of the stack to hold the 115 cowl thereon, a valve in the stack, said valve comprising a flat circular member having an annular flange on the upper surface thereof whereby to hold said valve out of contact with the top of the cowl, and means for 120 vertically moving the valve between the top of the stack and the cowl.

3. In a ventilator for buildings, a stack, right angularly arranged plates in the stack dividing the same into a plurality of flues, a 125 series of concentrically arranged spring fingers on the outer surface, a cowl having a conical top and said cowl engaged by the

spring fingers to hold the same on the stack, a flat valve normally resting on the top of the stack inward of the cowl, said valve having upon its outer surface a flange designed to contact with the top of the cowl to hold the valve out of such contact, angle plates on the under face of the valve and received in the respective flues and contacting with the walls thereof to guide the valve, and means for moving the valve vertically of the cowl 10 over the stack.

5 In testimony whereof I affix my signature.

ALFRED LAAKSO.
